[57] CLAIM

The ornamental design for an electrical leakage analyzer, as shown and described.

DESCRIPTION

FIG. 1 is a left front perspective view of an electrical leakage analyzer showing our new design;
FIG. 2 is a front elevational view thereof, the rear being flat, plain, and unornamented;
FIG. 3 is a left side elevational view thereof;
FIG. 4 is a right side elevational view thereof;
FIG. 5 is a top plan view thereof; and
FIG. 6 is a bottom plan view thereof.
